G. W. MORTER AND E. C. PACKER, OF ALLIANCE, OHIO.

Letters Patent No. 86,094, dated January 19, 1869.

IMPROVEMENT IN CHURNS.

The Schedule referred to in these Letters Patent and making part of the same.

To all whom it may concern:

Be it known that we, G. W. MORTER and E. C. PACKER, of Alliance, county of Stark, and State of Ohio, have invented new and useful Improvements in Churns; and we do hereby declare that the following is a full, clear, and exact description of our invention, reference being had to the accompanying drawings, forming a part of this specification, and to the letters of reference marked thereon, of which drawings—

Figure 1 is an end elevation of our improved churn.

Figure 2 is a plan of the same.

Figure 3 is a plan of a dasher and shaft.

Figure 4 are side and front elevations of the same.

Figure 5 are elevations of the two sides of the operating-wheel.

Figure 6 is a sectional view, showing mode of securing the churn-cover and dasher-shaft.

The nature of our invention consists in a novel mode of operating two upright dashers, in a common upright churn, whereby we obtain a rapid reciprocating and alternative movement of the dashers, and produce a violent agitation of the cream, and thus effect a rapid churning of the butter, the whole machine being so arranged as to be of simple and cheap construction, not liable to get out of repair, and easy to take apart and clean, all of which are essential features to a perfect churn.

To enable others skilled in the art to make and use our invention, we will proceed to describe its construction and operation.

The frame of the machine is composed of four principal uprights, A A and B B, which are united by side-pieces F F and E E, and cross-pieces G Y.

The rear uprights B B extend below the lower side-pieces E E, and form two of the feet of the machine, the feet X X, under the other ends of these side-pieces, forming the other feet.

The upper ends of the front uprights A A are formed as shown, and pass through holes in the sliding cross-piece H.

A board, D, is attached to the lower side of the lower side-pieces E E, directly under the uprights A A, and on this board is placed the churn R, which is secured in position by boards C C, which are cut out, to fit up to the churn, and are secured to the side-pieces E E, as shown, or the churn can be secured in any other suitable manner.

The churn R is of an ordinary form, and may be constructed of any suitable material.

Around the inside of the churn, and a little below the top edge of the same, is secured the rim g, which is of considerable width, and serves as a support to the covers h h, as well as to prevent the cream from slopping up and over the sides of the churn.

The covers h h are of a semicircular form, and fit together on the rim g of the churn, as shown, where they are secured by a bar, S, which is held down by a screw, Q, with nut b, bearing under the cross-piece Y, said screw passing up through the piece Y, and being operated by the head a at its top.

The dasher-shafts I I have the dashers W W, of an ordinary form, secured to their lower ends, and pass up through holes in the covers h h, and through slots

in the cross-piece Y, where they are secured by a strap-piece, O, which is pivoted to the cross-piece Y at one end, by a staple, c, the other end being secured, by the staple d, in the cross-piece Y, and the hasp P, on the strap o, in a manner readily seen.

The upper ends of the dasher-shafts I I are of a circular cross-section, and have the springs I I placed on them, as shown.

They project through holes in the cross-piece H, and the springs I I bear against the same piece, so that, by changing the height of said cross-piece, by means of the pins V V, which may be inserted in any of the holes in the uprights A A, the tension on the springs I I may be varied at pleasure.

The operating-wheel L is hung on a shaft, J, which is arranged in boxes on or in the upper side-pieces F F, said shaft J being provided with a crank, K, or any other suitable device for applying the power.

The pins M M and N N are inserted in the two sides of the wheel L, on lines at right angles to each other, as seen in fig. 5, and as the shaft J is revolved, they strike against the arms f f in the dasher-shaft I I, (see fig. 4,) and raise said dashers, until the pin M or N is drawn from under the arm f by the revolution of the wheel L, when the dasher I is forced down by the spring T.

A piece of rubber, e, is passed through a mortise in the dasher-shaft I, and strikes on the cross-piece Y, thereby stopping the downward movement of said dasher in an easy and effectual manner.

From the foregoing description, it is readily seen that, by turning the crank K, an alternate up-and-down movement of the dasher-shafts I I is effected, and through the action of the dashers W W, the cream in the churn R is thrown into violent agitation, and quickly churned.

The manner of removing the dashers I W, churn-covers h h, and churn R, for the purpose of cleaning the same, is too obvious to any person skilled in the art, to require particular description.

Having thus fully described our invention,

What we claim as new, and desire to secure by Letters Patent, is—

1. The peculiar arrangement and combination of the churn R, with broad inner rim g, covers h h, cross-bar S, press-screw Q, cross-piece Y, dashers I W, I W, and strap O, with hasp P and connecting-staples c d, the several parts being arranged as and for the purpose specified.

2. The peculiar arrangement and combination of the churn-dashers I W, I W, with arms f f, rubber stops e e, and springs T T; the adjustable cross-piece H and uprights A A with pins V V; and operating-wheel L with pins M M and N N; the several parts being arranged as and for the purpose specified.

As evidence that we claim the foregoing, we have hereunto set our hands, in presence of two witnesses, this 29th day of June, A. D. 1868.

G. W. MORTER.
E. C. PACKER.
